SPEEDBOAT

Charles T. Richardson, Bradley, Ill.

Application September 21, 1956, Serial No. 43,033

Term of patent 14 years

(Cl. D71—1)

Fig. 4

I claim:

The ornamental design for a speedboat, as shown.
